UNITED STATES PATENT OFFICE

FRANK CANNON, OF RHINECLIFF, NEW YORK

DIRECTION-INDICATING SIGNAL

Application filed September 20, 1927. Serial No. 220,812.

The present invention relates to a direction indicating signal particularly adapted for automobiles and has for its prime object to provide a structure which may be mounted on an automobile or the like to be seen from the front and rear and which embodies a pair of rotating disks operable by a pinion and rack structure through the medium of a plunger.

A still further important object of the invention resides in the provision of a signal of this nature which is simple in its construction, inexpensive to manufacture, strong and durable, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:—

Figure 1 is an end elevation of the signal embodying the features of my invention,

25 Figure 2 is a vertical section therethrough taken substantially on the line 2—2 of Figure 1,

30 Figure 3 is a top plan view of the signal showing a portion broken away in this section,

Figure 4 is a vertical section taken substantially on the line 4—4 of Figure 2,

35 Figure 5 is an enlarged detail section taken substantially on the line 5—5 of Figure 4, and,

Figure 6 is a detail section taken substantially on the line 6—6 of Figure 2.

Referring to the drawing in detail it will be seen that the numeral 5 denotes a cylindrical casing having end walls 6 closing the same. A partition 7 extends across the casing as a chord to form a segment compartment 8 the end wall 6 opposite this segment compartment 8 being formed with openings having lenses 9 therein with protecting shades 10 thereabout and extending outwardly therefrom. A shaft 11 is journaled in the end wall 6 coaxially with the cylindrical casing 5 and has fixed to the end portions thereof adjacent the end wall 6 disks 12 each of

which is provided with an annular series of openings 14 adjacent the periphery thereof with transparent signalling indicia 15 thereon which may be brought into registry with the lenses 9 by the rotation of the shaft 11 as will be clearly understood. The indicia on the transparent panels 15 will correspond so that the same signal will be given to the rear and to the front of the signal. A bulb 16 is located in the compartment 8 so that the indicia opposite the lenses 9 may be easily read from the front and rear of the automobile on which the signal is mounted. This signal may be mounted on the windshield or any other part of the automobile by a clamp bracket 17 or in any other suitable manner. In the bottom of the cylindrical casing there is provided a cylinder 18 with a plunger or piston 19 movable therein and a combined piston rod and rack bar 20 extending upwardly therefrom through an opening in the head of the cylinder and meshing with a pinion 21 on the center of the shaft 11. A pipe 22 leads through the bottom of the casing 5 to the interior of the cylinder 8 so that compressed air, exhaust gas, or the like may be conducted into the bottom of the cylinder to raise the plunger or piston 19 and actuate the rack bar 20 and rotate the pinion 21 for rotating the shaft 11 and the 55 discs 12 to place the desired panel 15 opposite the lenses 9 to give the desired signal.

A suitable circuit breaker 25 is disposed inside of the bottom of the cylinder 8 so that the plunger 19 will engage the same when in the bottom of the cylinder to break a circuit which will include the electric bulb 16 so that this electric bulb will be put out when the signal is inactive, that is, when the plunger 19 is in the bottom of the cylinder. 90

It is thought that the construction, operation, advantages, and utility of the invention will now be quite apparent to those skilled in this art without a more detailed description thereof. The present embodiment of the invention has been disclosed in detail merely by way of example since in actual practice it attains the features of advantage enumerated as desirable in the statement of the invention and the above description. It will be appar- 95 100

ent that changes in the details of construction, and in the combination and arrangement of parts may be resorted to without departing from the spirit or scope of the invention as 5 hereinafter claimed or sacrificing any of its advantages.

Having thus described my invention, what I claim as new is:—

A signal of the class described comprising 10 a cylindrical casing having vertical end walls, a shaft journaled in the end walls co-axially through the casing, a pinion on the shaft within the casing, a closed vertical cylinder rising from the bottom of the casing, a plunger 15 slidable in the cylinder, a combined plunger rod and rack bar engaged with the plunger and slidably mounted in the top of the cylinder and meshing with the pinion, a tube leading to the interior of the bottom portion of 20 the cylinder so that fluid may be used for raising the plunger to rotate the shaft, the end walls of the casing being provided with openings, and a disc on the ends of the shaft having indicia which may be brought into 25 registration with the openings.

In testimony whereof I affix my signature.

FRANK CANNON.
